US00D482032S

(12) United States Design Patent **(10) Patent No.:** **US D482,032 S**
Onozato et al. **(45) Date of Patent:** **** Nov. 11, 2003**

(54) DATA DISPLAY FOR ELECTRONIC COMPUTERS

D442,581 S * 5/2001 Su D14/336
D442,951 S * 5/2001 Hill et al. D14/336

(75) Inventors: **Akihiko Onozato**, Tokyo (JP); **Jun Katsunuma**, Tokyo (JP)

* cited by examiner

(73) Assignee: **NEC Corporation**, Tokyo (JP)

Primary Examiner—Freda Nunn

(74) Attorney, Agent, or Firm: Sughrue Mion, PLLC

(**) Term: **14 Years**

CLAIM

(21) Appl. No.: **29/169,109**

The ornamental design for a data display for electronic computers, as shown.

(22) Filed: **Oct. 16, 2002**

DESCRIPTION

(30) Foreign Application Priority Data

May 17, 2002 (JP) 2002-013229

(51) LOC (7) Cl. **14-02**

(52) U.S. Cl. **D14/371**

(58) Field of Search D14/371-382,
D14/125-129, 336, 337; 248/917-924;
341/12; 345/104, 156, 168, 173, 87; 348/180,
184, 325, 739; 349/1, 2, 11, 62

(56) References Cited

FIG. 1 is a perspective view of the top, front and left side of

a data display for electronic computers showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
